DISPENSER FOR FOLDED SHEETS

Nicholas Tuszynski, Milwaukee, Wis., assignor to
 Marathon Paper Mills Company, Rothschild,
 Wis., a corporation of Wisconsin

Application September 11, 1936, Serial No. 100,339

4 Claims. (Cl. 312—60)

This invention relates to a dispenser designed for dispensing folded sheets of paper one at a time intended for use by the attendants at gas and oil filling stations, for the purpose of wiping oil drippings or dust from a car or for like service, although the features of the invention are adapted to be incorporated into the structure of dispensers suitable for other purposes.

An object of the dispenser is to afford delivery of folded sheets singly from a stack, each sheet being folded to afford a body portion of the full cross-sectional dimensions of the dispenser and a free grasping tab adapted to be presented through a dispensing slot in position to be grasped between the thumb and finger of the user. Sheets of this character may be folded in various ways and with any number of plies, provided only that a free grasping tab of lesser dimensions than the body of the folded sheet is provided.

One of the objects of the present invention is the provision of means for properly guiding the folded paper sheets in relation to the dispensing slot so as to present the grasping tab and permit the withdrawal of only one folded sheet at a time.

Further objects and details will appear from a description of the invention in conjunction with the accompanying drawings, wherein,—

Figure 1 is a perspective view of the front of the dispenser with the first folded sheet therein in position for grasping.

Figure 2 is a perspective view of the rear of the dispenser.

Figure 3 is a perspective view of the dispenser with the hinged section in opened position.

Figure 4 is a plan view of the bottom slotted panel through which the sheets are dispensed.

Figure 5 is a perspective view of one of the side plates provided with guide flanges.

Figure 6 is an enlarged fragmental cross-sectional view taken on lines 6—6 of Figure 7.

Figure 7 is a cross-sectional view taken on lines 7—7 of Figure 1.

Figure 8 is an enlarged fragmental cross-sectional view taken on lines 8—8 of Figure 2.

Figure 9 is a cross-sectional view taken on lines 9—9 of Figure 8.

Figure 10 is an enlarged fragmental cross-sectional view taken on lines 10—10 of Figure 2.

The dispenser as a whole comprises a section 10 and a hinged section 11, the two sections being hinged upon pivots 12 at the forward lower corners so as to permit section 11 to be swung down into the position shown in Figure 3.

Section 10 includes a dished lower panel 31 rectangular in plan having a slot or aperture 31a and turned up lateral flanges 3. Section 10 also includes a back wall 2 of rectangular formation which is offset inwardly at its lower portion by 5 the provision of a shoulder 2a as shown in Figure 7 to fit within the lateral flanges of the bottom panel 31. The back wall 2 is provided at its upper edge with an inwardly extending flange 20. The back wall is integral with substantially 10 triangular end walls 9 which increase in width downwardly and fit within the lateral flanges 3 of the lower panel 31, being provided with an inwardly shouldered offset portion 7 which constitutes a continuation of shoulder 2a. 15

The section 10 has no front wall and is closed by hinged section 11 which is of complementary formation to give the dispenser a box-like configuration. The section 11 is so constructed as to have its edges overlap section 10 so that it 20 serves to shed rain and keep the contents perfectly dry.

The hinged section 11 includes a front wall 22, the lower edge of which overlaps the front flange 1 of the lower panel and integral triangular end walls 6 which overlap the obliquely disposed front edges 8 of the end walls 9, so that when the sections are closed as shown in Figures 1 and 2 the edges of the section 11 will overlap the edges of the section 10 throughout. The end walls 6 25 are cut away to form tongues 4a for receiving the pivots 12. The upper portion of the front wall 22 and triangular end walls 6 are provided with inwardly offset shoulders or flanges 4 which engage flanges 21 of the top 20. The top wall 20 30 is provided at its rear edge with an upstanding flange 22a. The front wall 22 is embossed as at 24 to provide a pleasing panel effect as shown in Figure 1.

In order to hold sections 10 and 11 in closed 40 relation a latch is employed which comprises a stem 13a and a handle 13. Stem 13a is provided with a rectangular slot 17 at its lower portion. The rear wall 2 is provided with a depressed portion 14, as shown in Figures 3 and 9, to receive 45 the stem 13a. A cover plate 15, shown in Figures 2 and 9 is affixed over the depressed portion 14 to form a channel for receiving the stem 13a. Cover plate 15 is cut out so as to provide a tongue 16 which projects inwardly as shown in Figure 8. 50 When stem 13a is pulled upwardly by handle 13 into the dotted line position shown in Figure 8 the lower edge 19 of the rectangular slot 17 will contact tongue 16 and prevent further upward movement of the stem. 55

In order to lock sections 10 and 11 together the handle 13 is raised up as far as it will move and section 11 is then swung into closed position over section 10. The handle 13 is then dropped 5 whereupon it will assume the position shown in Figure 8 and thereby lock section 11. Since flange 22a engages the inturned portion 13b of the handle it prevents section 11 from swinging outwardly.

10 A plate 25 is affixed to the rear wall 2 for providing means to suspend the dispenser on a wall or a post. Plate 25 is bent to provide a pair of inwardly directed flanges 27, which engage complementary flanges 29 of plate 30, the latter being 15 previously fastened to any supporting surface by means of screws 28a passing through holes 28 in plate 30.

Lower panel 31 is slotted to provide an elongated dispensing slot 31a having a lower straight lip 31b and an inwardly protruding upper lip 37. 20 Portion 31e of the panel is outwardly protruded to provide an outwardly diverging pocket as shown in Figures 1 and 7. The edges of the lips are folded inwardly as shown at 33, in Fig. 7 to 25 present a smooth, even edge.

The portion 34 of the bottom panel is inturned at its center portion so as to form an obliquely extending flange which is inwardly and upwardly bowed to afford a medial crest 37, from which 30 point the lip recedes on a curving line, outwardly and downwardly, until it merges into the general plane of the panel near the edges thereof thus forming a corner recession 31c at each end of the opening where the upper lip merges into the end edges 31d of the opening, which edges bow outwardly to connect with and merge into the lower lip. This configuration gives to the upper lip 37 both its greatest elevation and its greatest inward protrusion at or near the center crest, so 40 that this center portion will bear against the body 51 of the folded paper sheet having a free grasping tab 50 of lesser width than the body to permit the tab to clear the crest 37 of the lip as shown in Figures 1 and 7.

45 In order to hold the stacked sheets 60 in proper position in relation to the dispensing opening 31a, plates 40 are provided at the triangular walls 9 adjacent the opening. The plates 40 are provided as shown in Figures 3 and 5 with a pair of 50 flanges 41 and 42 which extend inwardly of the dispenser. Flange 42 is bent at approximately right angles to the body portion 43 and flange 41 is bent at an acute angle, so as to extend inwardly within the container. Flange 42 is comparatively narrow in width and extends the 55 length of the plate 40. Flange 41 is triangular in shape. Edge 44 of the plate is cut obliquely so as to be parallel to the edge 8 of the wall 9. A rectangular slot 45 is provided in the lower portion 60 of the plate so as to permit flange 7 to protrude therethrough thereby permitting the back of plate 40 to lie flush against the wall 9.

Flanges 41 and 42 serve to guide the edges of the folded sheets as clearly shown in Figure 6. 65 Owing to the inwardly bent flanges 41 the forward side portions 52 of the body portion 51 of folded sheets adjacent the dispensing slot are bent upwardly while permitting the tab portion 50 to drop through the dispensing slot 31a.

70 The construction of the flanges for guiding the folded sheets and the formation of the lips of the slotted panel 31 permits the smooth withdrawal of the folded sheets one at a time from the dispenser.

75 By forming the upper lip 37 with an upwardly

and inwardly protuberant center of the character described, the surface presented for contact with the sheets will be reduced so that the tendency to catch and hold the grasping tab and prevent its release will be overcome. At the same time the inward protrusion of the upper lip brings the point of support well toward the center of the stack, so that there will be no appreciable tendency for the sheets to sag down into the region immediately adjacent the dispensing slot.

The recession of the upper lip 37 toward the outer edges thereof brings these portions of the lip out of direct contact with the sheets, which contact is confined to the elevated center region of the lip, so that the edges of the sheets will release freely and with minimum friction as the sheets are being withdrawn.

The pocketed formation of the panel adjacent the lower lip is one which provides considerable space for the release of the lowermost grasping tab, and the separated relation of the upper and lower lips with respect to one another affords a widely extended aperture for the easy manipulation of the sheets.

The formation of the body of the container is 25 one which permits the top or cover portion thereof to be swung down into suspended relation with the upper portion, which completely exposes the back and bottom of the container and thus facilitates the introduction and positioning of a stack 30 of sheets. Although the dispenser as shown is positioned to feed the sheets downwardly without the use of weights, follower plates or the like, it will be understood that the dispenser might be so positioned as to present the slotted panel forwardly, in which case the folded sheets of the stack would stand vertically with the grasping tabs presented upwardly and outwardly, as is the common practice in dispensers of this general character. In such cases it may be desirable to 40 provide follower means of any well known and conventional form, which, however, form no part of the present invention and need not be specifically described.

Although the invention has been described with 45 particularity as to detail, it is not the intention to limit the invention strictly to the device as shown, since modifications may be made therein without departing from the spirit of the invention.

I claim:

1. A dispenser for sheets folded to each provide a body portion and a grasping tab of less width than said body portion comprising a box-like container having its lower wall in the form of a panel provided with an elongated dispensing slot, means 55 extending adjacent the ends of said dispensing slot for supporting the edge portions of the folded sheets and to bend them inwardly of the container, and permitting the grasping tab of the foremost sheet to extend through said elongated 60 slot.

2. A dispenser for sheets folded to each provide a body portion and a grasping tab of less width than said body portion comprising a box-like container having a bottom and side walls, said bottom wall being in the form of a panel provided with an elongated dispensing slot, a triangular flange affixed to each of the side walls and having its base lowermost and extending within the container over the ends of said dispensing slot and supporting the forward edges of the body portion of the folded sheets so as to bend them inwardly of the container, said dispensing slot being provided with a lip protruding within the container so as to contact the body portion of the foremost 70 75 80 85 90 95

napkin and permit the grasping tab of the foremost sheet to extend through the dispensing slot in position for grasping.

3. A dispenser for sheets folded to each provide 5 a body portion and a grasping tab of less width than said body portion comprising a box-like container having a bottom and side walls, said bottom wall being in the form of a panel provided with an elongated dispensing slot, two vertically 10 extending flanges affixed to each of the side walls and extending within the container in the region of the dispensing slot for guiding the napkins within the container, one of said flanges being substantially rectangular in shape and the other 15 of said flanges being substantially triangular in shape, the triangular flange having its base lowermost and extending over the ends of said dispensing slot and supporting the forward edges of the body portions of the folded sheets so as to 20 bend them inwardly of the container, said dispensing slot being provided with a lip protruding within the container so as to contact the body portion of the foremost napkin and permit the grasping tab of the foremost sheet to extend 25 through the dispensing slot in position for grasping.
4. A dispenser for a stack of sheets folded to each present a body portion and a grasping tab of less width than said body portion, comprising a box-like container having a bottom and side walls, said bottom wall being in the form of a panel provided with an elongated dispensing slot, two vertically extending flanges affixed to each of the side walls and extending within the container in the region of the dispensing slot for guiding the napkins within the container, one of 5 said flanges being substantially rectangular in shape and extending at approximately right angles to the plane of the side wall, the other of said flanges being substantially triangular in shape and extending within the container at an 10 acute angle to the plane of the end wall and extending over the ends of said dispensing slot and having its base lowermost and supporting the forward edges of the body portions of the lowermost folded sheets so as to bend said edges inwardly of 15 the container and permitting the tab portion of the foremost sheet to extend through said dispensing slot.

NICHOLAS TUSZYNSKI. 25
